UNITED STATES PATENT OFFICE.

CHARLES WANDERSEE, OF CHICAGO, ILLINOIS.

DESIGN FOR A SHAFT-TUG.

SPECIFICATION forming part of Design No. 28,809, dated June 7, 1898.

Application filed April 18, 1898. Serial No. 678,087. Term of patent 7 years.

To all whom it may concern:

Be it known that I, CHARLES WANDERSEE, a citizen of the United States, residing at Chicago, in the county of Cook and State of Illinois, have invented and produced a new and original Design or Useful Shape for Shaft-Tugs, of which the following, in connection with the accompanying drawings, is a full, clear, and exact specification.

In the said drawings, Figure 1 is a side elevation of a shaft-tug constructed according to my invention. Fig. 2 is a view looking at right angles to Fig. 1 or through the tug, and Fig. 3 is a plan section taken on the line 3 3, Fig. 2.

The leading features of my design are the shaft-tug loop A, having at the upper end or side two perforated ears 3 and at the lower inner side below such ears a plurality of bead-like or button-like formations C.

The loop A is egg shape, as viewed in Fig. 1 or when looking through it, and in side elevation it is a broad band having its edges more or less rounded, as shown in Fig. 3. It is also

slightly tapered from its lower side upwardly 25 toward the perforated ears B. On its extreme under side is formed a bulged portion a, and at each side of such bulged portion a and approximately under each of the perforated ears B is formed another perforated 30 ear D, as clearly shown in Figs. 1 and 2. Each of the button-like portions C, three of which appear, is rounded on its upper face, and the end ones taper downwardly to the surface of the inner side of the loop A, as clearly 35 shown in Fig. 2, and the entire series being seated in a cavity a', as shown in Fig. 3.

Having thus described my invention, what I claim as new, and desire to secure by Letters Patent, is—

The new and original design or useful shape for a shaft-tug substantially as herein shown and described.

CHARLES WANDERSEE.
